R. C. HOLMES ET AL

TREATING HYDROCARBON OILS

Filed Dec. 10, 1923

By their Attorney

R. J. Dearborn

UNITED STATES PATENT OFFICE.

RALPH C. HOLMES, OF NEW YORK, N. Y.; FREDERICK T. MANLEY, OF HOUSTON, AND OTTO BEHIMER, OF PORT ARTHUR, TEXAS, ASSIGNEES, BY MESNE ASSIGNMENTS, TO THE TEXAS COMPANY, OF NEW YORK, N. Y., A CORPORATION OF DELAWARE.

TREATING HYDROCARBON OILS.

Application filed December 10, 1923. Serial No. 679,569.

This invention relates to the cracking or decomposition of hydrocarbon oils for the production of gasoline and other similar products.

5 In carrying on the pyrogenic decomposition of hydrocarbon oils the production of coke and carbon which accompanies the operation establishes limitations to the operation, particularly in regard to the time under 10 which a given apparatus may be kept under operating conditions. One of the chief objects of the present invention is to provide methods and means that will result in prolonging the period of time during which the 15 still may be kept on stream. We attain this object by means of special apparatus and particular methods of operation in which either, or both, the charging of oil to the stills or the introduction of reflux condensate 20 thereto, is utilized to substantially eliminate or materially reduce the formation of excessive deposits of carbon or coke in the stills.

The chief difficulty encountered in carrying on the cracking operation is due to the 25 presence of the higher boiling oils, particularly the polymerized constituents which are formed in the cracking operation and which readily break down into carbon under the influence of heat. Thus when the heat required for the cracking operation is applied to the still the lower portion thereof, or those 30 portions which contain the bulk of the higher boiling oils or polymerized constituents, become heated excessively due to the rapid formation of carbon in these portions of the still. In the same manner when cracking is being carried on in a battery or plurality of stills those stills which contain liquid in the 35 more advanced stages of decomposition readily become overheated with a consequent excessive production of carbon and coke. In accordance with our invention the oil in those portions of the cracking zone which contains the bulk of the heavier hydrocarbons or polymerized constituents is diluted with the fresh oil charge, or with the reflux condensate obtained from the generated vapors, or with both charge and condensate, and thus the excessive production of carbon 40 and coke is prevented. The quantity of backtrap, or of charge, or of charge and backtrap, is so proportioned as to dilute the liquid in the cracking zone to the degree de-

sired so as to effect a successful and satisfactory operation.

In practicing the invention we preferably employ a battery or series of stills and selectively introduce the charge of oil into the stills so as to produce therein a greater or less amount of agitation and dilution of the oil undergoing conversion thereby preventing the excessive formation of carbon or coke deposits. We carry on distillation during the cracking operation, condensing a portion of the generated vapors, and reflux the condensate selectively to the stills. We prefer to employ a vertical still, or battery of vertical stills, and selectively introduce the charge and reflux condensate to the lower portions of the stills where the higher boiling and high carbon-forming oil tend to settle.

In carrying on the invention we prefer to preliminarily heat the oil to substantially the temperature desired for cracking and then introduce the heated oil to a cracking still or battery or series of stills or converters wherein cracking conditions are maintained. In thus operating we prefer to carry on the process in accordance with an invention described and claimed in a pending application of Otto Behimer Serial #263,562, filed November 21, 1918, wherein the oil is preliminarily heated to substantially a cracking temperature after which it is introduced into a still or converted wherein the bulk of the decomposition takes place. In the present process we pass the oil through a heated coil or passageway where the oil is heated under pressure to the temperature desired and then charge the heated oil selectively to the several stills of the battery, the oil preferably being introduced into the lower portions of the stills. The stills or converters are maintained under superatmospheric pressure but as they are ordinarily at a slightly lower pressure than that obtaining in the heating coil the effect of discharging the oil from the coil into the stills or converters is to produce a greater or less amount of agitation therein. If the oil in the coil be heated sufficiently that there is a substantial portion thereof in vapor form the agitating effect produced by the discharge of the stream of heated oil into the stills is augmented.

A special feature of our invention consists

in providing in the several stills or converters and in maintaining therein a body of liquid oil of substantially the same mean boiling point. We accomplish this result mainly either by the selective introduction of oil charge to the stills, or by the selective reflux of condensate to the several stills, or by the proper proportioning of reflux and charge to the stills, together with such control of the withdrawal of the liquid from the stills as may be necessary.

10 Another object of the invention is to provide suitable methods and means for starting a run and bringing the stills under operating conditions in a rapid manner as will be hereinafter more fully explained.

15 Another important object of the invention is to provide for the removal of the carbon from the various portions of the cracking 20 zone substantially in proportion to the extent of its formation, thereby prolonging the duration of runs.

25 For the purpose of giving a detailed description of the invention reference will now be had to the accompanying drawing which is a diagrammatic elevation showing apparatus constructed in accordance with the invention and constituting an embodiment thereof.

30 In the example of the invention thus illustrated 10 designates a heating coil which is mounted in a furnace 11, or otherwise arranged to be heated, and to which oil is supplied by means of a pump 12. It is to be understood that the oil may, prior to its introduction to the coil 10, be passed through suitable exchangers, such as tar and vapor exchangers, and through such economizers, or preheaters as may be desired, but as the 35 heat exchange apparatus which may be used constitutes in itself no part of the present invention no description of such apparatus is deemed necessary. A battery of cracking stills or converters, as 13^a, 13^b, 13^c, and 13^d 40 are provided in which the cracking operation or a material part thereof is carried on. The battery is shown as being composed of four stills but it is to be observed that any convenient number of stills may be employed to 45 advantage. The stills 13^a, 13^b, etc. are either arranged to be heated or are supplied with suitable insulation to prevent loss of heat due to decomposition, distillation and radiation. The stills illustrated are of the vertical type 50 and are interconnected in such a manner as to afford free communication between the several units of the battery. Thus the stills may be provided with interconnecting vapor lines 14 and liquid level lines 15 which, as 55 shown, are preferably arranged to establish communication between the upper portions of the several stills. The stills may, if desired, be equipped with scraping mechanism or with agitating or stirring means.

60 65 The coil 10 is provided with an outlet line

16 adapted to establish connection between the coil and the battery of stills or converters. As illustrated, the pipe 16 is provided with a plurality of valved branch lines 16^a, 16^b, etc. communicating with the several 70 stills. It is often sufficient to provide the pipes 16 with branches only to the first one, two or three stills of the series, since in most cases it is undesirable to charge into the latter stills of the series. There are at times, 75 however, advantages to be gained in charging to the last stills of the series and consequently it is convenient to provide means by which the oil may readily be charged into any or all of the stills of the battery.

80 Each still is equipped with a valved draw-off line, as 17^a, 17^b, etc. The several draw-off lines preferably terminate in a common draw-off pipe 17 which may lead to a suitable tar exchanger for preheating fresh oil 85 to be treated or it may lead directly to a storage tank. In carrying on the cracking operation it is best to do most of the charging of the oil to some of the stills of the 90 battery and rely on the others for the collection and withdrawal of the bulk of the residue containing the polymerized constituents and suspended carbon. We have found in practice that there is danger that the regular tar lines, from those stills in which the 95 greater portion of the carbon and polymerized bodies are sought to be withdrawn, may become choked by reason of excessive accumulations of carbon or coke. We, therefore, provide an auxiliary tar line 18 which is 100 equipped with branch lines, as 18^d and 18^e, extending to certain stills of the battery. In practice most of the tar is preferably drawn 105 through the bottom tar lines 17^d and 17^e, the line 18 being used mainly whenever it becomes necessary to remove additional liquid 110 for the purpose of equalizing the oil levels in the stills, and in case of emergencies, as in case the lines 17^d, 17^e would become coked, etc. We thus provide each still with means 115 for drawing off liquid or residue from the bottom thereof and equip certain of the stills, from which the bulk of the heavy residual material is to be removed, with additional lines in order to insure the ready withdrawal 120 of carbon and residue.

125 A vapor line 19 is provided for removing the generated vapors from the cracking stills and conveying them to a suitable condensing apparatus for liquefying a portion 120 of the vapors. The condensing apparatus preferably assumes the form of a fractionating apparatus, such as a bubble tower 20 in which the constituents of less volatility than that desired may be liquefied and collected 125 while the vapors of desired volatility may be permitted to pass out through a vapor line 21. A pipe 22 is provided for removing the condensate from the fractionating device 20. This pipe communicates with a 130

valved pipe 23 which is equipped with branch lines 23^a, 23^b, etc. communicating with the several stills. The condensate collected in the fractionating device 20 may thus be selectively refluxed to the several stills. The reflux lines 22, 23, 23^a, 23^b, etc., are preferably insulated. Any reflux liquid in excess of that desired to be returned to the stills may be removed from the system 10 by means of a valved pipe 24, which may connect with the line 17, as shown, or may extend direct to a tank.

The vapor line 21 preferably extends to a reflux condenser adapted to condense out 15 a portion of the vapors which may be returned to the fractionating device 20 by means of the valved pipes 25 and 26. A vapor line 27 extends from the reflux condenser 24 to a condenser 28. It is convenient 20 to provide pipe 25 with a branch line 25^a which connects with pipe 27 so that any water which may be condensed in the condenser 24 may be removed from the system. The condenser is provided with a valved 25 outlet 29 which terminates in a receiver 30, having a valved gas outlet 31 and a valved condensate pipe 32. The desired pressure may be maintained in the cracking stills by proper manipulation of the valves in the 30 lines, 19, 27, 29, 31 or 32. It is generally preferable to rely mainly on the valve in the gas outlet 31.

It will be observed that we provide the stills with a multiplicity of connections arranged in such manner that the carbon and heavy residual bodies may be readily withdrawn and a uniform oil level maintained in the several stills. By proper manipulation of the valves in the charging lines 16^a, 16^b, etc. in the backtrap lines 23^a, 23^b, etc. in the tar lines 17^a, 17^b, etc. or in the auxiliary tar lines 18^c and 18^d, the inflow and outflow of oil may be accurately regulated and at the same time such conditions maintained in the 45 several stills as are most conducive for an efficient and long time period of operation.

In commencing a run with the apparatus illustrated the oil is charged into the heating coil 10 and the fires for the furnace 11 are lighted. The oil enters the outlet pipe 16 and is then introduced to the battery of stills or converters. The particular method of charging the oil to the stills or converters depends on a number of variable factors. 50 Thus for example, in case the battery of stills is positioned in an end-fired furnace supplied with heat from a source adjacent the still 13^a it is desirable, in order to start the run in the most rapid manner, that the stills adjacent the firing end be filled with oil before the other stills are filled. In such a case the branch lines 16^b, 16^c, and 16^d may be closed leaving only the line 16^a open so that the entire quantity of oil from the heating coil is passed directly into the still 13^a.

When it is filled to the overflow line 15 the oil will pass into the still 13^b and thence into the others in succession. It is sometimes desirable to charge into stills 13^a and 13^b simultaneously, the exact procedure, of course, depending upon the particular furnace arrangement.

In case the stills are installed in a gas-fired furnace having for example, sets of burners, such as gas burners 33, adjacent each still and arranged at varying elevations, the best method of operation is to charge the oil into all of the stills thus raising the liquid levels in all of the stills simultaneously. It is practically impossible, however, to regulate the valves in the several branch lines 16^a, 16^b, etc., so that substantially the same quantity of oil will be charged into each still and for this reason the best procedure is to charge oil from the line 16 into say one or two of the stills, such as 13^a and 13^b, and having lines 16^c and 16^d closed, causing the oil to flow from the first two stills to the others in succession through the additional lines which it will be observed can be employed. Thus the valves in the lines 23^b and 23^c may be opened so that the oil charged into stills 13^a and 13^b may be passed into the remaining stills and the liquid levels in the several stills thus raised simultaneously. If desired, the draw-off lines 17^b, 17^c, 17^d and the special draw-off line 18^c may be employed for this purpose. It will be readily seen that by means of the several connections, as illustrated and described herein, it is possible to convey the oil to all of the stills at the same time so that the oil levels in the several stills may be raised simultaneously. Thus the lower rows of burners may be lighted at an early stage and the rows of burners above lighted as the oil levels in the several stills rise with the result that the battery may be brought under running conditions practically as soon as the stills are full of oil. The time required for starting a run and getting a battery on stream is thus materially reduced.

After the stills have been brought to operating conditions it is preferable that the flow of liquid between the stills be through the liquid level lines 15 rather than through the bottom connections provided for quick starting. The oil is heated in transit through the coil 10 so that it is discharged through the outlet 16 at the temperature desired, which is preferably substantially a cracking temperature. The heated oil is continuously passed into the particular stills desired and in such proportions thereinto as is considered desirable. Thus the oil may be charged, for example, wholly into still 13^a and caused to flow to the other stills in succession, or it may be charged into stills 13^a and 13^b, or it may even be charged into

stills 13^a, 13^b, and 13^c. When charging into still 13^a or stills 13^a and 13^b, the stills 13^a and 13^b, particularly the latter, are relied on for the collection of the carbon and residual matters and consequently the bulk of the oil drawn off will be from stills 13^c and 13^a, particularly the latter still. In this method of operation the valve in the tar line 17^d is opened most frequently and held open for the longest intervals, while shots of progressively decreasing frequency and interval are taken from stills 13^c, 13^b, and 13^a, respectively. In this way the polymerized bodies contained in the residual oil may be removed from the stills before they are broken down into free carbon and the carbon that is formed and which is held in the liquid in suspension may be removed approximately in proportion to its formation and before injurious deposits of carbon or coke have resulted.

The backtrapping or refluxing of condensate from the separator 20 is preferably regulated in accordance with the system of charging employed so as to maintain oil of substantially the same boiling point in the several stills, except in perhaps the last one or two from which the bulk of the residue is withdrawn. It is generally undesirable to backtrap any material quantities into the still or stills from which the bulk of the residuum is withdrawn because in so doing the residue drawn off is contaminated with the reflux which constitutes potential gaso-line-forming material. It is to be observed, however, that at times it is quite advantageous to reflux even into the draw-off stills. Thus when there are evidences of excessive coking or formations of carbon in certain of the stills the backtrap may be introduced into such stills so as to flush same out and check the production of coke deposits before any material injury has occurred. At times due to uneven heating in the furnace or to other causes certain of the stills may have a tendency to rise in temperature unduly with a resultant excessive production of coke or carbon. This tendency may be overcome by introducing sufficient reflux to such stills. In the case of end-fired furnaces it is particularly advantageous to reflux a considerable portion of condensate to the still or stills which are subjected to the more intense furnace heat and in this way prevent overheating of such still or stills.

One method of operation that has been found advantageous is to introduce the oil charge from the coil 10, and the reflux condensate or backtrap, to certain of the stills in regulated proportions. Thus for example, with the lines 16^c and 16^d closed the valves in the lines 16^a and 16^b may be so regulated as to admit approximately $\frac{2}{3}$ of the charge of oil into the still 13^a and $\frac{1}{3}$ into the still 13^b. The backtrap lines 23^a and

23^b are normally closed except when necessary for flushing purposes and the valves in the lines 23^a and 23^b are so regulated as to admit $\frac{1}{3}$ of the backtrap to the still 13^a and $\frac{2}{3}$ to the still 13^b. The proportions stated are given as an example to indicate the possibility of regulating the flow of oil charge and backtrap to the several stills in order to obtain the most desirable results. When introducing a material quantity of charge and backtrap to a selected portion of the cracking zone, such for example as stills 16^c and 16^b, it is desirable to carry a temperature in the outlet of the coil 10 above the temperature desired to be maintained in the stills.

Although the preferred embodiment of the invention has been set forth in connection with apparatus having a particular construction and arrangement of parts and mode of operation, it is obvious that various changes and modifications may be made therein, while securing to a greater or less extent some or all of the benefits of the invention, without departing from the spirit and scope thereof. Therefore, only such limitations should be imposed as are indicated in the appended claims.

What I claim is:

1. The process of cracking hydrocarbon oils which comprises heating the oil to substantially a cracking temperature, passing the heated oil into a plurality of converters wherein cracking conditions are maintained, condensing a portion of the generated vapors and selectively refluxing said condensate to the several converters.

2. The process of cracking hydrocarbon oils which comprises heating the oil to substantially a cracking temperature, selectively introducing the heated oil into a plurality of stills wherein cracking conditions are maintained, condensing a portion of the generated vapors and selectively returning the condensate to the several stills.

3. The process of cracking hydrocarbon oils which comprises maintaining oil under cracking conditions in a plurality of stills, condensing a portion of the generated vapors and selectively returning condensate to the several stills in such manner as to maintain the oil in the several stills at substantially the same mean boiling point.

4. The process of cracking hydrocarbon oils which comprises maintaining oil of substantially the same mean boiling point in a plurality of stills wherein cracking conditions are maintained, by selectively charging oil to said stills, by selectively withdrawing liquid from the stills and by selectively refluxing to the several stills condensate formed from the vapors generated.

5. The process of cracking hydrocarbon oils which comprises heating the oil to substantially a cracking temperature, selec-

- 65 tively charging the heated oil into a plurality of converters wherein the oil is maintained under cracking conditions, condensing a portion of the generated vapors and selectively returning condensate to the converters, while maintaining a predetermined ratio between the quantity of oil charged, and the quantity of condensate returned, to each of the several converters.
- 66 10. The process of cracking hydrocarbon oils which comprises maintaining a body of liquid oil at a cracking temperature and superatmospheric pressure with a substantially uniform liquid level in a plurality of stills, by selectively charging oil to said stills, by withdrawing vapors from the stills, by condensing a portion of the vapors and selectively refluxing condensate to the several stills, and by selectively withdrawing liquid from the stills.
- 67 15. The process of cracking hydrocarbon oils which comprises heating the oil to substantially a cracking temperature, passing the heated oil selectively to stills of a battery of stills wherein superatmospheric pressure and cracking temperature is maintained, withdrawing vapors and liquid from the stills, condensing a portion of the vapors and selectively admitting condensate to the several stills.
- 68 20. In the cracking of hydrocarbon oils by subjecting same to cracking temperatures and pressures in a battery of stills, the process that comprises initially introducing the oil into one of the stills of the battery and passing the oil thence to the other stills in succession through lines interconnecting the lower portions of the stills, and then while continuing to charge oil to the battery discontinuing the passing of oil through said lower interconnecting lines and passing the oil from one to the other of the stills in succession through lines interconnecting the upper portions of the stills.
- 69 25. In the cracking of hydrocarbon oils by subjecting same to cracking temperatures and pressures in a battery of stills, the process that comprises initially heating the oil and charging it into one of the stills of the battery and passing it thence to the other stills in succession through lines interconnecting the lower portions of the stills, and then, while continuing to charge oil to the battery and heating said oil to substantially a cracking temperature, passing it through the stills in succession through lines interconnecting the upper portions of the stills.
- 70 30. The process of cracking hydrocarbon oils which comprises heating the oil to substantially a cracking temperature, passing the heated oil selectively to certain of the stills of a battery, drawing off the bulk of the residue from certain other stills of the battery, condensing a portion of the generated vapors and refluxing selectively to the several stills of the battery.
- 71 35. The process of cracking hydrocarbon oils which comprises heating the oil to substantially a cracking temperature, passing the heated oil selectively to stills of a battery of stills wherein cracking conditions are maintained, drawing off residue from the last still of the series at certain intervals and for certain periods of time and drawing off liquid from the other stills from the last to the first of the series at progressively decreasing intervals and for progressively decreasing periods of time.
- 72 40. Apparatus for cracking hydrocarbon oils comprising a plurality of stills, vapor equalizing and liquid level lines interconnecting the stills in series, means for introducing oil to the stills comprising a manifold line with valved branches to the several stills adapted to selectively admit the oil to the stills severally, a reflux condenser adapted to receive vapors from the stills and means for returning condensate from said reflux condenser to the several stills comprising a manifold line with valved branches to the several stills.
- 73 45. Apparatus for cracking hydrocarbon oils comprising a plurality of vertical stills, lines interconnecting the upper portions of the stills in series, means for selectively introducing oil to the lower portions of the several stills, means for removing vapors from the stills, means for condensing a portion of said vapors, and means for selectively returning condensate to the several stills.
- 74 50. Apparatus for cracking hydrocarbon oils comprising a heating coil, a battery of stills, means for selectively charging oil from the coil to the several stills, means for condensing a portion of the vapors from the stills, and means for selectively admitting condensate to the several stills.
- 75 55. Apparatus for cracking hydrocarbon oils comprising a heating coil, a battery of stills, means for selectively charging oil from the coil to the several stills, condensing means in connection with the stills, means for conducting condensate from said condensing means and selectively admitting same to the stills severally, and means for selectively drawing off liquid from the lower portions of the stills.
- 76 60. Apparatus for cracking hydrocarbon oils comprising a heating coil, a battery of vertical stills, lines interconnecting the upper portions of said stills, means for selectively charging oil from the coil to the several stills, a vapor conduit from said battery of stills, condensing means in communication with said conduit, a condensate line adapted to receive condensate from said condensing means, branch lines extending from the condensate line to the several stills, and

means for drawing off liquid from the lower portions of the stills.

17. Apparatus for cracking hydrocarbon oils comprising a heating coil, a battery of 5 vertical stills, pipes interconnecting the upper portions of said stills, a manifold in communication with the coil and comprising valved branch lines to the several stills, a vapor line from the stills, condensing means 10 in communication with said vapor line, a condensate line adapted to receive condensate from said condensing means, valved branch lines extending from said condensate line to the several stills, a draw-off line having 15 valved branch lines to the several stills and an auxiliary draw-off line with valved connections to certain of the stills.

18. Apparatus for cracking hydrocarbon oils comprising a heating coil, a battery of 20 vertical stills, pipes interconnecting the up-

per portions of the stills, a manifold in communication with the coil and comprising valved connections to the lower portions of the several stills, means for condensing a portion of the vapors from the stills, a condensate line arranged to receive the condensate, valved pipes extending from said condensate line to the lower portions of the several stills and valved draw-off lines extending from the lower portions of the stills.

means for drawing off liquid from the lower portions of the stills.

17. Apparatus for cracking hydrocarbon oils comprising a heating coil, a battery of 5 vertical stills, pipes interconnecting the upper portions of said stills, a manifold in communication with the coil and comprising valved branch lines to the several stills, a vapor line from the stills, condensing means 10 in communication with said vapor line, a condensate line adapted to receive condensate from said condensing means, valved branch lines extending from said condensate line to the several stills, a draw-off line having 15 valved branch lines to the several stills and an auxiliary draw-off line with valved connections to certain of the stills.

18. Apparatus for cracking hydrocarbon oils comprising a heating coil, a battery of 20 vertical stills, pipes interconnecting the up-

per portions of the stills, a manifold in communication with the coil and comprising valved connections to the lower portions of the several stills, means for condensing a portion of the vapors from the stills, a condensate line arranged to receive the condensate, valved pipes extending from said condensate line to the lower portions of the several stills and valved draw-off lines extending from the lower portions of the stills.
